CLOSURE AND RECEPTACLE

Emerson E. Hogg and Eli Frank Andersen, New Kensington, Pa., assignors to Aluminum Company of America, Pittsburgh, Pa., a corporation of Pennsylvania

Application March 23, 1935, Serial No. 12,642

4 Claims. (Cl. 215—39)

This invention relates to an external closure for receptacles and it relates particularly to a definite relationship between the closure and the neck finish of the receptacle.

A great amount of attention has been devoted in the past, and is still being devoted, to the problem of making seals or closures for receptacles of various sizes, shapes and materials of a tamperproof nature, i. e., that cannot be removed without either visible alteration or destruction of the closure. It is an object of our invention to provide this desired tamperproof characteristic by means of combinations of receptacle finish and closures, so that an attempt

15 to remove a closure will leave visible alterations and also so that removal will destroy the closure. It is an additional object of our invention to create this desirable characteristic in a combination utilizing well known forms of closures that hitherto have lacked this quality. The importance of this accomplishment is unquestionable in the light of contemporaneous marketing tendencies. The period of retailing from bulk is now one that belongs largely to the past. In the

20 constant search for attractive containers, bottles have, of course, received attention, but it has been a drawback in the advancement of some uses of them that seals of tamperproof character have added disproportionately to the cost of packaging. It is a further purpose of the present invention to overcome this objection and to make available a tamperproof combination at a cost no greater than that of ordinary known closures.

The accomplishment of these objects gives the invention particular advantage in the marketing of liquids, in which line of commerce there has been in the past great chance for dilution and alteration of contents. In this field the invention permits the retention of the sales advantage found in the display offered by glass receptacles and at the same time provides the consumer with an assurance that the producer's true product is being purchased. A striking example of a product where this advantage is of primary importance is found in the retail marketing of lubricating oils.

Additional objects and advantages of our invention will appear in the detailed description and the accompanying drawing, in which:

Fig. 1 is an elevation, partly in section, dis-

50 closing the invention with a closure employing a tear-off tab included in the combination;

Fig. 2 is an elevation, partly in section, dis-

closing the invention with a shallow beaded clo-

sure shell included in the combination;

Fig. 3 is an elevation, partly in section, dis-

closing the invention with an ordinary crimped skirt closure included in the combination; and

Fig. 4 is an elevation, partly in section, dis-

closing the invention with a crimped skirt closure and over-all liner included in the combination.

In Figs. 1 through 4, by which our invention is illustrated, like parts bear the same reference numbers. A neck finish that is for practical purposes common to all of the figures includes a bottle neck 1 having an annular bead 2 imme- 5 diately adjoining the mouth of the bottle. The under side of the bead 2 inclines inwardly and downwardly to a narrow annular neck portion which forms the base of the groove 3. The groove 3 is defined on its lower side by the upper surface of a second annular bead or ledge 4. This surface of bead 4 preferably extends perpendicularly to the base of the groove 3, although this surface may be inclined slightly upwardly from the base to the periphery thereof. Furthermore, the bead 4 extends a substantial distance beyond the periphery of bead 2 in order to completely accommodate the skirts of various known types of closures. 10

Referring now to Fig. 1, there is shown an ordinary form of closure employing a tear-off tab 5 which preferably has weakened portions on the top surface and in the skirt to facilitate tearing and removal of the closure shell. A shallow skirt 6 is turned under the bead 2 by any suitable method, as by rolling, and is compressed into the narrow groove 3. This means of retaining the closure guarantees a suitable seal between the compressible insert 7 and the top sealing surface of the bottle immediately adjacent to the mouth. The same deformation of the skirt forces the bottom edge thereof against the top surface of the ledge 4, with the result that an attempt to effectuate removal of the closure from the bottom is made extremely difficult, since the ledge 4 does not readily accommodate a tool capable of loosening the skirt. In case an attempt is made to remove the closure in this fashion the thin skirt will be permanently mutilated, and should the closure be so removed it will be so torn and 15 disfigured that it will not be replaceable. 25

In Fig. 2 the neck finish described above is shown with a simple closure comprising a one-piece shell having a shallow skirt 6 and compressible sealing insert 7. The bead 2 in this modifi- 30 cation presents a cylindrical portion from the horizontal plane of the mouth to that of the groove 3 with which the skirt 6 is held in close contact by the lower skirt portion which is turned under the bead 2 and into the groove 3. In this 35 40 45 50 55

modification the closure has no means integral therewith for removal from the bottle neck. The means and method for effecting removal will be discussed below, since it is common to Fig. 2 5 and the following Figs. 3 and 4.

In Fig. 3 a form of closure of known type, commonly called a crown, is shown as a part of our combination. In this type of closure the thin shallow skirt 6 has a fluted or crimped bottom edge and the corrugations thereof, when forced 10 under the retaining bead, as shown in Fig. 3, form a perfect seal between the compressible sealing insert 7 and the top sealing surface of the bottle. Ordinarily a closure of this type is 15 removed by force exerted against the crimped bottom edge by well known forms of bottle openers for which the top surface of the closure serves as a fulcrum. According to our invention the bead or ledge 4 is so proportioned and so located 20 that the crimped edge of the closure is held against the bead and as a result a tool cannot be inserted between the bead and closure to remove the latter.

In Fig. 4 there is shown a closure having a 25 shell of the same type as shown in Fig. 3. This embodiment, however, differs from Fig. 3 in that it discloses an over-all liner or sealing insert 7 that separates the skirt 6 of the closure shell from the bead 2 and groove 3 of the neck finish. 30 This interpositioning of the insert results in a thickness of insert and shell approximating the width of the bead or ledge 4. As is shown in Fig. 4, the crimped bottom edge and the insert of the closure are forced into close contact with the 35 ledge 4. In this modification of the invention it is apparent that the relationship of ledge and closure makes the removal of the closure by insertion of a tool even more difficult than in the previous forms. Furthermore, as in the previous 40 forms, because of the manner in which the lower skirt portion is held between the closely placed beads, any attempt to remove the closure will be readily discernible, and should the closure be removed it will not be reuseable.

45 The advantages of our invention must now readily appear and the opportuneness of our contribution to the closure art is striking in that it satisfies the strong present demand for inexpensive closures to be applied to reuseable containers. With the exception of the form illustrated in Fig. 1, it is necessary to remove and thereby destroy the closure by an auxiliary means and, furthermore, it is apparent from the very 50 essence of our invention, the relationship of skirt and bead, that removal must be accomplished from the top surface of the closure. The structure of the tool used for this purpose forms no part of this invention, since it is clear that a tool sharp enough to puncture the closure and of

satisfactory shape and strength to permit the closure to be pried off will be satisfactory. This use of an opener before the customer to not only break the producer's seal upon the receptacle but also to destroy the closure has a forceful sales advantage that cannot be overlooked. 5

It is, of course, appreciated that our invention is in no way limited to the specific embodiments by which we have herein illustrated it. Therefore, with the intent to include all forms coming 10 within the spirit and true scope of our invention, we claim:

1: A tamper-proof combination of bottle finish and closure comprising a bottle neck having an annular peripheral bead adjoining the mouth, 15 an annular ledge beneath the bead, a narrow annular groove separating said bead and ledge, and an external closure, said closure having a deformable skirt portion disposed under said bead and extending into said groove with the bottom thereof forced tightly against said ledge, 20 said ledge extending beyond the skirt portion in contact therewith to prevent bottom removal of said closures.

2. A tamper-proof combination of bottle finish 25 and closure comprising a bottle neck having an annular peripheral bead adjoining the mouth, an annular ledge beneath the bead, a narrow annular groove separating said bead and ledge, and an external closure, said closure having a shallow 30 deformable skirt continuously disposed under said bead and extending into said groove with the bottom thereof forced tightly against said ledge, said ledge extending beyond the skirt portion in contact therewith to prevent bottom removal 35 of said closure.

3. A tamper-proof combination of bottle finish and closure comprising a bottle neck having an annular peripheral bead adjoining the mouth, 40 an annular ledge beneath the bead, a narrow annular groove separating said bead and ledge, and an external closure having a skirt portion bearing crimped detents, said skirt portion having the detents disposed under said bead with the skirt edge forced tightly against said ledge, 45 said ledge extending beyond the skirt edge in contact therewith to prevent bottom removal of said closure.

4. In a sealed container having a mouth bead and an external metal closure retained by a skirt portion constricted below said bead, a continuous 50 annular ledge extending outwardly from the container and having the bottom of said constricted skirt portion bearing tightly against the upper surface thereof to produce a tamperproof container. 55
